UNITED STATES PATENT OFFICE.

HARRIE A. BALLARD, OF BOSTON, MASSACHUSETTS, ASSIGNOR TO THE BOYLSTON MANUFACTURING COMPANY, OF SOUTH BOSTON, MASSACHUSETTS, A CORPORATION OF NEW JERSEY.

DIVIDED LAST.

1,118,523.

Specification of Letters Patent.

Patented Nov. 24, 1914.

Application filed May 4, 1908. Serial No. 430,890.

To all whom it may concern:

Be it known that I, HARRIE A. BALLARD, of Boston, in the county of Suffolk and State of Massachusetts, have invented certain new and useful Improvements in Divided Lasts, of which the following is a specification.

This invention has relation to lasts such as are employed in connection with the manufacture of boots and shoes.

The object of the invention is to provide a last which is capable of being longitudinally shortened or contracted, so that it may be easily removed from a shoe, and which at the same time is capable of withstanding the various pressures to which it is subjected in the manufacture of the shoe and particularly in the leveling operation.

On the accompanying drawings, I have illustrated a last embodying my invention, and I have shown how it may be utilized in connection with a tree so that it may be employed practically throughout the process of manufacturing a shoe.

Figure 1 illustrates a tree foot with my last thereto attached. Fig. 2 represents a similar view, and shows the last shortened from end to end by moving one of the parts thereof transversely with reference to the other. Fig. 3 represents a section on line 3-3 of Fig. 1. Fig. 4 represents a longitudinal section through the last, and also illustrates the tree leg member which moves the locking device in position to free the two parts of the last. Fig. 5 is a similar section through the last, and shows the forepart and heel part in position to permit the entrance of the last into a shoe or its withdrawal therefrom. Fig. 6 represents an enlarged section on the line 6-6 of Fig. 5. Fig. 7 illustrates the lower end of the tree leg in section.

The last is illustrated as being made of a single block which is sawed or divided by a transverse cut into two sections indicated at *a* and *b*. The plane of intersection between the two parts is inclined or oblique from the top of the last rearwardly toward the heel end, so that, when one of the parts or sections is moved transversely relatively to the other part, the last, as a whole, will be shortened from end to end so that it may be easily inserted into or removed from a shoe. The two confronting faces of the

forepart *b* and the heel part *a* of the last are formed with aligned slots or grooves indicated at *a'* *b'*, which extend from the top to the bottom of said parts; and placed in said grooves is a connection consisting of a web or flat plate *c* which has a sliding fit therein without any appreciable lost lateral motion. This plate is formed or provided with four slots longitudinally of its length, these slots being indicated at *c'*, *c*², *c*³ and *c*⁴. The slots are all parallel to the confronting or abutting faces of the forepart and heel part, and the slots *c'* and *c*³ may be in alignment with those at *c*² *c*⁴ respectively, as shown in the drawings, though this is not essential.

Passed transversely through the forepart are two pins or fasteners *d* *d'* which extend through the slots *c'* *c*², there being passed through the heel part two similar pins or fasteners *d*² *d*³, which pass through the slots *c*³ *c*⁴. These pins or fasteners are so located that, when the heel part and forepart are in their normal positions, as shown in Fig. 4, the pins *d* *d'* will be seated against the upper ends of the slots *c'* and *c*², and the pins *d*² *d*³ will be seated against the lower end walls of the slots *c*³ *c*⁴. By reason of this construction, it will be apparent that there is possible a relative movement between the plate *c* and the forepart *b*, and between the plate *c* and the heel part *a*, in consequence of which, there is a relative movement of the heel part and forepart to a distance substantially twice the length of the slots *c'* and *c*³ or *c*² and *c*⁴ less the thickness of two of the pieces, as shown in Fig. 5. The pins *d*, *d'*, *d*², *d*³ are in sliding engagement with the web or plate and they constitute means projecting laterally from the said web or plate for preventing the longitudinal separation of the forepart and heel part.

I provide for locking each of the two parts *a* and *b* to the plate *c*, and to this end I employ a lock which is indicated at *e*. This consists of an elongated metallic plate which is located in a groove or recess *c*⁵ in one face of the plate *c*. The lock *e* is fulcrumed upon a pivot *f*, passed into the plate *c*, and it is formed or provided with two shoulders *e'* *e*² on opposite sides of the pivot which may be engaged with the pins or fasteners *d* *d'* respectively, as shown in Fig.

4. The lock is held yieldingly in this position by a spring g , and it may be moved into the position shown in Fig. 5 so as to release the plate from the pins and permit 5 a relative movement of the two parts a and b and the plate c . When the forepart and heel part are brought into alinement or into their normal positions, the lock is moved automatically by the spring into its active 10 position, where its faces or shoulders e' e^2 engage the pins d^3 and d , so that the forepart is locked rigidly against transverse movement relatively to the heel part, the plate being locked relatively to each of said 15 parts. The provision of the four pins in connection with the plate, makes a strong, stiff last that is not liable to get broken; and by permitting relative movement of the plate, the forepart and the heel part, 20 a greater amount of movement of one of the said parts relatively to the other is secured than if the plate were rigidly secured to one of said parts. The lower end of the plate conforms to the curvature of the bottom or 25 shank of the last, but a portion of its upper end projects beyond the last, the latter being cut away, as at h , to expose a pin or projection e^3 on the lock. The pin or projection e^3 permits one to engage the lock and 30 move it into inactive position, as shown in Fig. 5.

The top of the heel part is illustrated as flat and as being covered with a plate i which may be of leather or other suitable 35 material, leather being preferably used when the last is to be employed in connection with a tree leg. In the heel part is formed the usual spindle socket j for receiving a spindle on the tree leg.

40 I have illustrated a convenient form of tree leg with which the last may be employed. As shown in Figs. 1, 2 and 3, the leg is formed of two sections k k' which are secured together in any convenient way. 45 Between them is a hollow chamber k^2 , see Fig. 7, in which is located a lock-operating device m . This device consists of a flat, curved metallic slide having slots m' , through which pass pins m^2 which hold it in 50 place, and which guide its movement. The lower end of the slide has an inclined edge m^3 which may engage the projection e^3 on the lock and swing the lock about its pivot when the said lock-operating device is 55 forced downwardly. The first downward movement of the slide unlocks the portions of the last, and during its continued downward movement, the end of the said slide engages the forepart of the last and forces 60 it to the position shown in dotted lines in Fig. 1.

The slide m is operated by a lever n , the lower end of which is partially circular and which is seated in a complementary 65 socket m^4 in said strip. The upper end of

the lever n has a handle n^2 by which it may be manipulated. It likewise has an elongated slot n^3 through which passes a pin n^4 inserted transversely into the tree leg k .

I do not wish to be understood that the lever n and slide m are the only devices which may be utilized to unlock the sections of the last and to move the forepart to an inactive position since any other equivalent mechanism could be utilized for the same purpose. The mechanism which I have illustrated, however, is simple and serves the purpose.

The tree leg is provided with a cylindrical spindle o which enters the spindle socket in the heel part of the last. For the purpose of locking the heel part to the spindle, I utilize a rod p , the lower end of which is wedge-shaped as at p' , so that, when the rod is drawn longitudinally of the leg by any usual or convenient means, the wedge will slide along the inclined face o' of the spindle and bind the heel part to the spindle.

Having thus explained the nature of my said invention and described a way of constructing and using the same, although without attempting to set forth all of the forms in which it may be made or all of the modes of its use, I declare that what I claim is:—

1. A two-part divided last comprising two sections having obliquely inclined confronting faces, one of said sections being movable with respect to the other in a plane parallel to said faces, and a connecting plate slidably connected to each of said sections to move relatively thereto in lines substantially parallel to the face thereof.

2. A divided last comprising a heel part and a forepart having obliquely-inclined confronting faces, one of said parts being bodily movable relatively to the other in a plane parallel to said faces, said parts having opposing recesses, a connecting member located in said recesses and slidably connected to each of said parts to move relatively thereto in lines substantially parallel to the face thereof, and means for locking said heel part and forepart against their relative movement.

3. A divided last comprising but two sections, to wit, a forepart and a heel part having confronting oblique faces, a member for connecting said parts to hold them against relative movements lengthwise of the last, and means for slidably connecting said member with each of said parts to move relatively thereto in lines parallel to its face.

4. A divided last comprising two sections having confronting faces, one of said sections being bodily movable relatively to the other in a plane substantially parallel to said faces, and said faces having recesses, and movable relatively to each section in

lines substantially parallel to the said confronting faces, a connecting member slidably extending into the said recesses, and means extending laterally from said member into engagement with said sections for preventing longitudinal separation of said sections.

5. A divided last comprising two sections of which one is bodily movable at an inclination to the other in lines parallel to their plane of division, said sections having longitudinal grooves, a member arranged in said grooves, and a pin and slot connection between said member and each of said sections to permit relative movement thereof, said slots being substantially parallel to said plane of relative movement of said sections.

6. A divided last comprising two sections of which one is bodily movable at an inclination to the other in lines parallel to their plane of division, said sections having longitudinal grooves, a member arranged in said grooves, a pin and slot connection between said member and each of said sections to permit relative movement thereof, said slots being substantially parallel to said plane of relative movement of said sections and means for locking said member to each of said sections to hold them against relative movement.

7. A divided last comprising a heel part and a forepart having inclined confronting faces and longitudinal recesses, a connecting member slidably seated in recesses in said faces, means for connecting said parts to said member to permit a limited rectilinear sliding motion of said member relatively to both said parts in lines substantially parallel to said faces, and a lock carried by said member for locking each of said parts thereto.

8. A divided last comprising a heel part and a forepart having longitudinal grooves or recesses, a transverse pin in each of said parts, a longitudinally arranged member slidably seated in said grooves or recesses in the said parts, said member having slots parallel to the respective faces of the heel part and forepart to receive said pins, in consequence of which said member has a limited movement relatively to each of said parts, and means for locking said member to said pins.

9. A divided last comprising a heel part and a forepart having longitudinal grooves or recesses, a transverse pin in each of said parts, a longitudinally arranged plate slidably seated in said grooves or recesses in the said parts, said plate having slots to receive said pins, in consequence of which said plate has a limited movement relatively to each of said parts, and a lock pivoted on said plate and having shoulders for engaging said pins to lock the plate to said parts.

65 10. A divided last comprising a heel part

and a forepart, having longitudinal recesses in their confronting faces, a plate located in said recesses, and having slots substantially parallel to the said faces, and two pins in each of said parts passing through slots in said plate, all so arranged that said forepart, said heel part and said plate are capable of a limited movement relatively to each other.

11. A divided last comprising a forepart 75 and a heel part having faces obliquely inclined from the top of the last toward the heel end and relatively movable in lines parallel to said faces, a plate seated in recesses in said faces, means for connecting said plate to one of said parts, a pin and slot connection between said plate and the other of said parts, and a pivoted locking device carried by said plate for locking said last-mentioned part against movement relatively to said plate.

12. The combination with a divided last comprising two relatively slidable sections, of which the heel part has a spindle socket, a slide connection between said sections for 90 permitting a bodily movement of said sections parallel to their plane of division, and a lock pivoted on said connection for locking said sections against relative movement, of a tree leg constructed and arranged for 95 coöperating with said last and having a spindle arranged to enter said socket, and also having a slide arranged to engage said lock and move it to unlocking position.

13. The combination with a divided last 100 comprising a heel part and a forepart having obliquely inclined confronting faces, a connection which inseparably connects said sections slidably together and a lock for holding said sections against relative movement, of a tree leg constructed and arranged 105 for coöperation with said divided last comprising a spindle for engagement with the heel part, a slide arranged to move said lock to inactive position and to move the forepart 110 relatively to the heel part to permit the removal of a shoe, and means by which said slide may be operated.

14. A divided last comprising two sections having obliquely inclined confronting 115 faces, one of said sections being movable in a plane parallel to said faces and a connecting device to slide relatively thereto substantially parallel to the face thereof slidably engaged with each of said sections for 120 permitting said described movement but holding said sections against longitudinal separation.

15. A divided last comprising a heel part and a fore part having confronting faces, 125 one of said parts being movable bodily relatively to the other in a plane parallel to said faces and both of said parts having alined recesses, and a connecting device extending into each of said recesses and arranged to 130

slide therein in lines parallel to said faces, means for preventing the longitudinal separation of the said fore part and heel part, and means for locking said heel part and 5 said fore part together.

16. In a divided last, heel and toe portions provided respectively with internal parallel key-ways; and a sliding connecting member or key extending from one portion 10 to the other and slidingly engaged in each of said key-ways.

17. In a last, a heel part and a toe part sliding on each other to lengthen and to shorten the last, and having a vertical groove 15 in the meeting face of one part; a plate connected to the second part and projecting into said groove, and having a slot parallel with said meeting face; a cross-pin in the first part passing through the slot; and a tilting dog carried by the plate, and arranged to engage the pin to lock it in the 20 end of the slot to hold the two last parts in the lengthened position.

18. In a last, a heel part and a toe part 25 sliding on each other to lengthen and to shorten the last, and having a vertical groove in the meeting face of one part; a plate connected to the second part and projecting into said groove, and having a slot 30 parallel with said meeting face and a recess adjacent to and connecting with the slot; a cross-pin in the first part passing through the slot; and a tilting dog held in said recess, and arranged to engage the pin to lock 35 it in the end of the slot to hold the last parts in the lengthened position.

19. In a last, a heel part and a toe part sliding on each other to lengthen and shorten the last, and having a vertical 40 groove in the meeting face of one part; a plate connected to the second part and projecting into said groove, and having a slot parallel with said meeting face; a cross-pin in the first part passing through the slot; and a tilting dog carried by the plate, and arranged to engage the pin to lock it in the 45 end of the slot to hold the last parts in the lengthened position, said dog having a lateral projection arranged to be engaged to tilt the dog and unlock the parts.

20. A divided last comprising a heel part and a forepart, one of said parts having a vertical groove in its confronting face, and a pin extending across said groove, a plate 50 connected to the other last part and projecting into said groove, said plate having a slot parallel to said confronting face for the reception of said pin, and a member movably mounted on said plate for engaging said pin

to lock said plate with relation to said 60 grooved part.

21. A divided last comprising a heel part and a forepart, a plate connected to and projecting from one of said parts into the other, said other part having a groove for 65 relative sliding movement of said plate, said plate having a slot within said grooved part, a transverse member in said grooved part, and extending across the groove therein and through the slot in said plate, and a locking member carried by said plate for engaging 70 said transverse member to lock it in one end of the slot, said locking member being retractible for releasing said transverse member.

22. A divided last comprising a heel part and a forepart, a plate connected to and projecting from one of said parts into the other, said other part having a groove for 75 relative sliding movement of said plate, said plate having a slot within said grooved part, a transverse member in said grooved part, and extending across the groove therein and through the slot in said plate, and a locking member carried by said plate and mounted 80 to tilt thereon, said locking member being arranged to engage said transverse member 85 to lock it in one end of said slot.

23. A divided last comprising a heel part and a forepart, a plate connected to and projecting from one of said parts into the other, said other part having a groove for 90 relative sliding movement of said plate, said plate having a slot within said grooved part, a transverse member in said grooved part, and extending across the groove therein and through the slot in said plate, and a spring- 95 pressed locking member carried by said plate, and arranged normally to lock said transverse member in one end of said slot.

24. A divided last comprising two sections, a plate slidably connected to each of 100 said sections, and a movable lock on said plate for locking said plate to each of said sections.

25. A divided last comprising two sections, a plate slidably connected to each of 110 said sections, and a movable lock on said plate for locking said plate to each of said sections, said lock having a portion projecting above the top of the last by which it may be operated.

In testimony whereof I have affixed my signature, in presence of two witnesses:

HARRIE A. BALLARD.
